UNITED STATES PATENT OFFICE.

CHRISTEN NIELSON, OF NEW YORK, N. Y.

BORING-MACHINE.

SPECIFICATION forming part of Letters Patent No. 639,604, dated December 19, 1899.

Application filed August 6, 1898. Serial No. 687,954. (No model.)

To all whom it may concern:

Be it known that I, CHRISTEN NIELSON, a resident of New York, (Brooklyn,) county of Kings, and State of New York, have invented 5 certain new and useful Improvements in Boring-Machines, of which the following is a full, clear, and exact specification, reference being had to the accompanying drawings, wherein—

Figure 1 is a plan and Fig. 2 a sectional view of a drilling-vise and gage combined made according to my invention. Fig. 3 is a plan view of such adjustable drilling-vise and gage combined; Fig. 4, a sectional view on line 4 4, indicated in Fig. 3. Fig. 5 is a front 15 and Fig. 6 a side elevation of a vertical drill provided with my combined adjustable vise and gage. Fig. 7 is a sectional view of the automatic stopping device used in connection with my combined drilling-vise and gage.

20 My invention relates to boring-machines; and it consists of the herein-described combined vise and gage devised for boring of frame of roller bearings for fifth-wheels and for similar work of this character wherein it is required that the borings be made exactly 25 in the line of the diameter and either equidistantly from each other or in points marking equal or proportionate fractions of the circles. Antifriction-rollers used in the construction of roller-bearings for fifth-wheels are mounted between two concentric circular rails on spindles which must be exactly in the 30 radial line of the rails in order to avoid strain and friction, which is detrimental to the working of the bearing. They must also be apportioned equidistantly from each other. Heretofore the boring of such rails was done 35 separately for each rail, the holes having been previously marked thereon. The process is slow and tedious and the result of such work not satisfactory. The spindles of the rollers must fit tightly into the holes. They must be exactly in the radial line; otherwise the 40 rollers would not revolve and the bearings would not work. If the holes deviate from the exact radial line, the holes must be filed, and then, aside from the greater amount of labor involved, the bearings do not work satisfactorily and are speedily worn out, because 45 the spindles do not sit firmly in such irregular holes, and consequently the rollers mount-

ed thereon joggle and twist themselves in the channels of the bearing-plates.

My invention also obviates the otherwise prerequisite dividing and marking of the 55 rails, and renders it possible to bore both rails at the same time in an exactly radial line. My combined vise and gage renders it also possible to bore a number of such holes simultaneously through both rails and of exact size as required for the spindles of the 60 rollers, thus obviating all necessity of subsequent adjusting the holes by reaming or filing.

My non-adjustable vise and gage consists 65 of a segmental block A, provided with a number of concentric grooves $a a'$, $b b'$, $c c'$, &c., arranged in pairs varying in depth, width, and the intervening distance between each two composing a pair, series of bores 1 2 3, 70 $a a'$, $b b'$, $c c'$, &c., the removable automatic stopping device B, and of means for affixing the block to the platform of a drill. Grooves $a a'$, $b b'$, $c c'$, &c., represent parts of circles corresponding to the diameters of the rails, and the bores 1 75 2 3, &c., follow radial lines of the circles. The widths of grooves $a a'$, $b b'$, &c., correspond to the thickness of the rails, and the sizes of bores 1 2 3, &c., are in all series the same as are also the sizes of the spindles to 80 be set in the rails and the distances between the bores of each series are equal, representing equal divisional parts of the circumference of the outside circle of each corresponding pair of rails. The distances between the 85 bores vary in each series, being dependent upon the number of rollers required for the various sizes. The divisions of all series are started from the common radial line $x x$, in which the bores of all series (and sizes) coincide. All bores are arranged on the same 90 level; but the depths of the grooves $a a'$, $b b'$, $c c'$, &c., vary correspondingly to the width of the rails for each size of bearings.

Screw-threaded holes z serve for removably 95 affixing to block A the automatic stopping device B in position corresponding to the division of the size of rails being bored. The stopping device consists of bow j , pin i , collar k , spiral spring m , fork n , and lever l , 100 fulcrumed therein. Pin i is snugly fitted into bores 1 2 3, &c., and sufficiently long to

reach from the apex of bow beyond the outer groove a of the last pair in the block. The pin is inserted in a bore provided in the apex of bow j and is provided with a number of 5 transverse holes p' , adapted to receive pin p , which holes are as far apart as the several pairs of grooves $a a'$, $b b'$, $c c'$, &c., are arranged in the block. Inside of the bow j and between its apex and adjustable collar k 10 spring m is slid on the pin i , driving the pin inwardly. The stem of fork n is also snugly fitted in the bores 1 2 3, &c., and thus the fork may readily be set in the bore nearest to that in which pin i is inserted and its position as readily changed as that of the pin. 15 Lever l is pivoted between the tines of the fork n , and its shorter forward arm is joined by links o to pin p , and thereby to pin i . By pressing upon the other end of lever l , which 20 is made in the shape of a handle, the pin is drawn outward against the action of the spring m .

The combined vise and gage can also be made adjustable for boring rails of various 25 diameters and of varying thickness. The adjustable combined vise and gage shown in Figs. 3 and 4 consists of the base-plate D , provided with integral flanges D' and D^2 and with radial slots E , having their lower edges 30 beveled to receive the heads of screws u , by means of which segmental strips v and v' are secured to the base-plate. Strips v are rectangular in cross-section, whereas strips v' are partly recessed, so as to form a groove 35 when joined to strips v . The width and depth of this recess corresponds to the width and thickness of the rails, and thus the width and depth of the grooves formed by joining strips v' to strips v may be varied. Flange 40 D' and also strips v and v' are provided with bores 1 2 3, &c., the flange with bores of all divisions, whereas strips v and v' are provided only with the bores corresponding to the divisions of the rails for which they are 45 designated. Strips v and v' are exchangeable, and thus permit adjustment of the combined vise and gage not only for rails of varying diameters, but also for varying widths between the rails.

50 The functions of the implement will be most readily understood from the following explanation of its use: Block A is secured to the platform of a drill—for instance, a vertical drill—in the manner shown in Figs. 5 and 6 by bolts q and in such position that line xx and the plane of bores 1 2 3, &c., are in alignment with the axis of the drill-spindle. The set or pair of rails to be drilled (t and t') are then inserted in the corresponding 55 pair of grooves $a a'$, $b b'$, or $c c'$, &c., and then secured together by clamps s , s' , and s^2 . Then the drill is started, the drilling-tool entering the bore in line with line xx and is driven successively through both the outer 60 and the inner rail. Stopping device B is then set on the edge of block A in line with the

next following bore of the corresponding division, preferably to the left of the drill-spindle, and pin i is adjusted to enter the bore sufficiently deep so as to cross the groove 70 in which the outer rail t of the pair is inserted. At the start of the boring operation the rail will bar the pin i from crossing the groove; but after the first hole is drilled pin i will slip into it when the rails are shifted, 75 and thereby arrest the rails exactly in position in which the next following hole is to be drilled. All that the operator has to do, after once adjusting the combined vise and gage, is to press upon the handle of lever l after 80 each successive hole is bored, to withdraw pin i from the outer rail and then shift the rails along the respective grooves $a a'$ or $b b'$, &c., until the further motion is arrested by the pin i dropping into the next following (or 85 last-drilled) hole. The rails may be secured in the grooves by clamps or other devices while the drilling is being done. It is, however, not necessary, because the rails are fully inclosed in the grooves, and owing to 90 their curvilinear shape the very slight clearance between the rails and the walls of the grooves, and also owing to the circumstance that the two rails are clamped together and the outer one is being held in the block by 95 the pin i , cannot be displaced accidentally.

Besides the advantages stated above the use of my combined gage and vise avoids all danger of bending the rails during the drilling and prevents the forming of burs around 100 the holes.

I claim as my invention—

1. A combined drilling-vise and gage comprising a block, series of grooves, representing segments of concentric circles, arranged 105 in pairs, provided on the face of the block and series of radial bores running transversely through the strips bounding the grooves, and dividing the peripheries of the circles, represented by each pair of grooves in equal sections. 110

2. A combined drilling-vise and gage comprising a flanged base-plate, segmental strips secured to the base-plate and forming a series of grooves representing segments of concentric circles, arranged in pairs, means for securing the strips to the base-plate; series of radial bores, representing equal divisions of circles of various diameters, provided in the outer flange of the base-plate, and series of 115 radial bores running transversely through the strips bounding the grooves and dividing the peripheries of the circles, represented by each pair of grooves in equal sections. 120

3. An automatic stopper comprising a bow, 125 a bore in the apex of the bow, a stop-pin provided with a series of transversal holes, a cross-pin set in one of the transversal holes beyond the bow movably set in the bore a collar adjustably secured to the pin within the bow, a 130 spiral spring set on the pin between the collar and the apex of the bow, a standard, a

two-armed lever fulcrumed in the standard and means for flexibly connecting one end of the lever to the stop-pin.

4. The combination with a combined drill-
5 ing-vise and gage comprising a block, series
of grooves, representing segments of concen-
tric circles, arranged in pairs, provided on the
face of the block and series of radial bores
running transversely through the strips
10 bounding the grooves and dividing the pe-
ripheries of the circles, represented by each
pair of grooves in equal sections, of an auto-
matic stopping device comprising a bow, a
bore in the apex of the bow, a stop-pin pro-
15 vided with a series of transversal holes, a cross-
pin set in one of the transversal holes beyond

the bow movably set in the bore, a collar ad-
justably secured to the pin within the bow, a
spiral spring set on the pin between the col-
lar and the apex of the bow, a standard, a 20
two-armed lever fulcrumed in the standard,
links pivotally connected to one end of the
lever and to the stop-pin, and means for se-
curing the bow and the standard to the block.

In witness that I claim the improvements 25
described in the foregoing specification I have
signed my name in the presence of two sub-
scribing witnesses.

CHRISTEN NIELSON.
